RUDOLF MURN, OF LAKEWOOD, OHIO.

ICE-CREEPING ATTACHMENT.

1,169,857.

Specification of Letters Patent.

Patented Feb. 1, 1916.

Application filed October 18, 1915. Serial No. 56,461.

To all whom it may concern:

Be it known that I, RUDOLF MURN, citizen of the United States, residing at Lakewood, in the county of Cuyahoga and State of Ohio, have invented certain new and useful Improvements in Ice-Creeping Attachments, of which the following is a specification.

My invention relates to an ice creeping attachment adapted to be secured to the instep of a shoe to prevent slipping on an icy walk, all substantially as shown and described and particularly pointed out in the claim.

15 In the accompanying drawings, Figure 1 is a side elevation of a shoe having my improved device affixed thereto, and Fig. 2 is a bottom view of the shoe with the device as in Fig. 1. Fig. 3 is an enlarged bottom view of the device alone, and Fig. 4 is a cross section on line 4—4, Fig. 3. Fig. 5 is a cross section on line 5—5, Fig. 3.

The device as thus shown comprises two sections or parts *a* and *b* slidably related and confined together in this instance by overturned edge portions 2 and 3 on one of said parts across the edges of the other part, or equivalent means, and provided each with a jaw 4 and 5 respectively at its outer end adapted to clamp over or upon the sole of a shoe in the instep relatively as seen in Figs. 1 and 2, and to fasten the device firmly on the shoe. The larger or main part *a* has a forward extension or tongue 6 on the bottom 30 and front of which are two sharp teeth or spurs 7, and which come forward a sufficient distance beneath the instep and have sufficient depth in themselves to more or less penetrate the ice or icy surface or street for 35 which they are intended, but are not so far forward nor of such length that the device 40 comes into the flat tread of the shoe itself or interferes with the walking on ordinary pavements. In other words, the said spurs 45 are the forward inclined shank portion of the instep and in a precautionary but not obstructive position and where the shoe is

merely supplemented by spurs which will penetrate sufficiently to make walking safe on slippery surfaces. The said jaws or lips 50 4 and 5 are curved somewhat both lengthwise and in cross section to conform to the edge of the sole to which they are affixed, and the extremity of lever 8 is bent inward 55 at its extremity to avoid interference in walking.

A light metal is employed to make all the parts and the sections *a* and *b* are drawn together and clamped on a shoe by such means as a lever 8 pivoted to rotate horizontally on the bottom of part *a* and having a link connected therewith near its pivot 10 and with the said part *b* near its middle. The said parts are so constructed and related that when the device is clamped in 60 place on the shoe the link 9 will be drawn across the dead center of pivot 10 and thus lock the device in place. A reverse movement of the lever releases the device. 70

What I claim is:

An ice creeping attachment for the instep of a shoe comprising a main plate having one edge curled downward and inward to engage on the edge of the sole and provided with opposite parallel upwardly and inwardly turned edges transversely of the shoe forming guide-ways and having a forwardly projected portion widened at its extremity and pointed spurs on said extremity adapted to come under the forward portion 75 of the instep, an auxiliary plate slidably mounted in said guide-ways and having a curled outer edge adapted to engage the edge of the sole, and a lever pivoted on said main plate and a link engaging the lever 80 with said auxiliary plate to clamp said plates on the shoe. 85

In testimony whereof I affix my signature in presence of two witnesses.

RUDOLF MURN.

Witnesses:

GEO. E. KRICKER,
R. B. MOSER.
